UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,584, dated October 18, 1881.

Application filed August 25, 1881. Term of patent 3½ years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

A vine, A, traverses the entire paper, and is formed into series of convolutions, terminating in leaves, tendrils, flowers, and fruits. There are clusters *l* of berry-like fruits, a pear-shaped fruit, *m*, and there are flowers of various

outlines, as indicated at *a*, *b*, *c*, *d*, *e*, *f*, *g*, and *j* in the photograph. Between the convolutions ²⁰ of the stem A are representations of various insects—a bee, *n*, above the flower *c*, a butterfly, *h*, another butterfly, *i*, a caterpillar, *o*, below the pear—all tending to give a peculiar life-like feature to the entire design.

I claim—

The design for wall-paper, consisting of the vine A and ornamentations *a*, *b*, *c*, *d*, *e*, *f*, *g*, *l*, *m*, and *j* thereon, and of the ornaments *h* in *o*, substantially as shown.

EDUARD LEISSNÈR.
